UNITED STATES PATENT OFFICE

103,024

DESIGN FOR A REFRIGERATOR LATCH

Raymond Loewy, New York, N. Y., assignor to Sears, Roebuck & Co., Chicago, Ill., a corporation of Illinois

Application October 31, 1934, Serial No. 53,832

Term of patent 3½ years

To all whom it may concern:

Be it known that I, Raymond Loewy, a citizen of the United States, residing at New York, county of Kings, and State of New York, have invented a new, original, and ornamental Design for a Refrigerator Latch, of which the following is a specification, reference being had to the accompanying drawing, forming part thereof.

Figure 1 is a front elevational view of a refrigerator latch, showing my new design.

latch.

I claim:

The ornamental design for a refrigerator latch
as shown.

RAYMOND LOEWY.
